LIQUID COOLER

Harry E. Crosby, Huntington Park, Calif., assignor to Mission Dry Corporation, Ltd., Los Angeles, Calif., a Corporation of Delaware

Application October 20, 1930. Serial No. 489,993

1 Claim. (Cl. 62—141)

This invention relates to an improved refrigerator unit, and has for one of its principal objects the provision of means for use in refrigeration, which means shall be more efficient than the ordinary units now in use, particularly so far as actual exposure of cooling surface is concerned.

One of the important objects of this invention is to provide in a refrigerator unit or the like means for adding additional working surface for contact with the material to be cooled without increasing the actual operating size of the unit to any noticeable extent.

Another and still further important object of the invention is to provide in a refrigerator unit or the like means for an additional reservoir space whereby an extra amount of refrigerant is available at all times, and further whereby a reserve is created for automatic use in the event of any special emergency.

Other and further important objects of the invention will be apparent from the disclosures in the accompanying drawing and following specification.

The invention, in a preferred form, is illustrated in the drawing and hereinafter more fully described.

In the drawing:

Figure 1 is a side elevation of the improved refrigerator unit of this invention, parts being broken away to show interior construction.

Figure 2 is a partial sectional view taken on the line 2—2 of Figure 1, looking in the direction indicated by the arrows.

Figure 3 is an end view of the improved unit.

As shown in the drawing:

The reference numeral 10 indicates generally a metal cylinder or the like which constitutes the expansion chamber for the improved refrigerator unit of this invention, this cylinder being adapted to contain a liquefied gas 12 which is maintained in liquid form under pressure as in the usual device, the liquid entering the chamber through an inlet pipe 14 controlled by a valve 16 operated by means of a float or the like 18. The gas in the upper part of the chamber is drawn off through an outlet pipe or the like 20.

One of the important novel features of this invention resides in the provision of extra contact surface for the refrigerating chamber by extending from this chamber smaller communicating chambers as illustrated at 22, and which comprises pipes or cylinders either made integral with or mounted in the cylinder, preferably at the bottom thereof, in a gas-tight manner. These communicating chambers or hollow fin-

gers project from the wall of the main chamber, and may be of any desired size and dimensions, the chief purpose being, of course, to provide a maximum contact surface, and in the usual practice are from one-third to one-half the height 60 of the main chamber and extend downwardly from the bottom wall thereof. The positioning of these chambers could, of course, be radial or at other angles, and they also could extend from the sides or top of the chamber, although in 65 practice it has been found that the degree of cold obtained is slightly greater in the bottom position. The form of the communicating chambers could also be varied, as instead of a plurality of cylindrical extensions, one or more trough-like 70 extensions could be used.

The unit itself is shown as adapted for cooling a liquid in a container 30, this being shown as circular in cross-section as best indicated in Figure 2, and with a dome-like top and bottom 34 and 36 respectively. An inlet for water or some other liquid to be cooled is shown at 38, and an outlet at 40, and it will be evident that the type of container for the liquid may be varied 75 as desired, and that further other substances than liquids may be cooled, such as air or the like.

In operation the liquefied gas feeds into the chamber 10 through the pipe 14 and past the inlet valve 16, the intake being controlled by the float valve 18. The liquid fills the extensions 22 and also the main chamber 10 to about one-third of its height, and as the liquid gasifies and the level falls, the valve opens and permits an added 80 supply to enter. This operation, of course, is usual in such constructions, the gasified refrigerant being drawn off through the pipe 20, or an expansion valve could be used in this connection. The cooled liquefied gas in the extensions 22 provides a very considerable added cooling contact 85 surface for the liquid or substance to be cooled, and further, these extensions will always contain a considerable reserve amount of the refrigerant. Obviously, if the extensions are positioned at the 90 top or higher sides of the cylinder 10, they will be filled with gas instead of liquid, but the cooling action will take place in much the same manner, and an extra cooling surface for an ordinary sized unit will be provided.

I am aware that many changes may be made and numerous details of construction varied throughout a wide range without departing from the principles of this invention, and I, therefore, do not purpose limiting the patent granted here- 105 110

on otherwise than as necessitated by the prior art.

I claim as my invention:

A cooling unit for liquids, comprising a chamber, inlet and outlet pipes for the chamber, and a refrigerating unit in the chamber, said refrigerating unit including a cylinder, and hollow cylindrical extensions on the lower portion of the

cylinder and extending into the liquid to be cooled for providing additional contacting cooling surface said extensions provided with closed ends, together with a liquid inlet pipe and a gas outlet pipe for the cylinder, and a float valve 80 control for the inlet pipe.

HARRY E. CROSBY.
